CYLINDER HEAD FOR INTERNAL COMBUSTION ENGINES

Josef Bořík, Prague, and Jiri Klos, Koprivnice, Czechoslovakia, assignors to Tatra, národní podnik, Koprivnice, Czechoslovakia

Filed Apr. 18, 1962, Ser. No. 188,491

Claims priority, application Czechoslovakia Jan. 18, 1961
11 Claims. (Cl. 123—41.57)

This invention relates to cylinder heads for internal combustion engines, and more particularly to a cylinder head for air-cooled high-power, high speed engines.

In its more specific aspects, this invention is concerned with problems arising in air-cooled compression ignition engines of large size and operating at very high compression ratios in which the bottom of the cylinder head is subjected to extreme thermal stresses. The compression ratio, and the efficiency of such engines is determined to a significant extent by the necessity of keeping thermal stresses below the limit determined by the high-temperature ultimate mechanical strength of the materials of construction employed.

It is known to provide cylinder heads of such engines with turbulence chambers and pre-combustion chambers which somewhat contribute to lowering of the temperature at the cylinder head bottom. Such chambers, however, are not always desirable, and cannot be employed where fuel is directly injected into a combustion chamber formed within the top face portion of the piston. In engines of the latter type, additional chambers can be provided in the head only at a loss in volumetric efficiency, or at a loss in the efficiency of fuel use.

It is an object of the invention to provide a cylinder head for engines of the type described which can absorb a heavy thermal load without excessive mechanical weakening of the materials of construction, and without compromising the design of the combustion space.

Another object is the provision of a liquid cooled cylinder head for an air-cooled internal combustion engine.

A more specific object is the provision of a liquid-cooled cylinder head which does not require an additional conduit system for the circulation of a liquid coolant.

With these and other objects in view, this invention in one of its specific aspects contemplates to provide the cylinder head of an internal combustion engine of the above-described type with a trough shaped cavity so that one of the opposite faces of the lid portion of the cylinder head constitutes the bottom of the trough whereas the other face closes the top of the engine cylinder in the assembled condition of the cylinder head.

The head carries the usual rocker-actuated overhead valves and the fuel injection nozzle. The valve rockers are lubricated by a continuous stream of oil, as is conventional, and the lubricating oil released from the rocker bearings overflows into the trough-shaped cavity of the cylinder head and thence into the crankcase. It continuously takes up caloric energy from the head and dissipates it in other parts of the engine which are under lower thermal stress.

These and other features and the attendant advantages of this invention will be more fully appreciated as the same becomes better understood by reference to the following detailed description of a preferred embodiment thereof when considered in connection with the accompanying drawing wherein:

FIG. 1 shows a cylinder head of the invention in section on an axial plane; and

2

FIG. 2 is a plan view of the head of FIG. 1.

The cylinder head of the invention consists mainly of a lid portion 1 which covers the open top of the combustion space in a cylinder 2, and of an integral annular wall portion 4 which extends upwards away from the lid portion 1. The two portions of the cylinder head respectively constitute the bottom and side wall of a trough-shaped or substantially frustum-shaped cavity.

The downwardly directed face of the lid portion 1 is apertured in the usual manner to provide two valve seats 3 for an air intake and an exhaust valve respectively.

A central bore 7 in the lid portion 1 which extends upwardly into a tubular boss 6 provides tight seating for a fuel injection nozzle in the usual manner, the nozzle itself not being shown. Ribs 8 which project upwardly from the lid portion 1 connect the boss 6 with the wall portion 4 near the bottom of the trough. Fuel reaches the nozzle through a bore 18.

The lid portion 1 has its smallest thickness near the boss 6, and increases in thickness toward the wall portion 4. The lower face of the lid portion 1 is approximately flat, whereas the upper face is approximately spherically concave. The wall portion 4 decreases in thickness in a direction upwardly away from the lid portion 1 in such a manner that the cavity in the cylinder head flares upwardly toward its open top. The free rim of the wall portion 4 constitutes a reinforced frame 5. Fins 19 on the outside of the wall portion 4 promote cooling by ambient air.

30 A conduit 9 is integrally formed in the wall portion of the cylinder head and has a slightly projecting orifice 9' in the upper half of the cavity. The conduit 9 extends downwardly from the orifice 9' and communicates with the crank case of the engine through an aligned bore in the cylinder block when the cylinder head is installed. Only one cylinder 2 of the cylinder block is partly shown in the drawing since it is conventional and not directly a part of this invention.

35 An exhaust port 10 and an air inlet port 11 are provided in the cylinder head in a basically conventional manner, and communicate with respective valve seats 3 in the lid portion 1. A projection 12 extending upward into the cylinder head cavity above each valve seat 3 is provided with a bore 13 which serves as a guide for the stem of a

40 respective valve, not itself shown.

45 Apertured bosses 14 on the frame 5 receive the end portions of respective through bolts 20 (shown in FIG. 1 only) by means of which the cylinder head is normally fastened to the cylinder block, the crank case, and other

50 elements of the engine as is usual.

55 It will be understood that movement of the valves whose stems reciprocate in the guide bores 13 is actuated by rockers mounted above the cylinder head and operating against the pressure valve springs coiled about the valve stems. The springs normally hold the valves in the closed position, and the valves are opened by the rockers in timed sequence against the force of the springs. The rocker assembly is not illustrated since it is known in itself, but the threaded openings 16 in which it is anchored in the operative condition of the engine are seen in FIG. 2. The rockers are actuated by valve lifter rods passing through openings 17.

60 The rockers are lubricated by a constant stream of oil. The rockers are arranged above the open top of the cavity in the cylinder head, as is apparent from the location of the lifters and the valve stems, and the lubricant is permitted to flow from the rocker assembly directly into the cavity, filling the same to the level of the orifice 9'.

When the cavity is filled to that level, any excess overflows continuously into the crank case of the engine through the conduit 9, to be recirculated from there.

The lid portion 1 of the cylinder head is very much hotter than the wall portion 4, and the oil at the bottom of the trough-shaped cavity is rapidly heated. It expands and rises, drawing relatively cool oil to the bottom. Although fresh oil is supplied from the top of the cavity, and excess oil is drawn off from a point at or near the top of the body of oil in the cavity, there is effective thermosyphon circulation of oil in the cavity, and the lid portion 1 is cooled by the circulating oil. This cooling effect is enhanced by the surface increasing ribs 8 in the cavity since the grooves between the ribs are filled with oil. The oil also acts as a heat transfer medium between the lid portion 1 and the finned wall portion 4, but heat flow between the several portions of the cylinder head is believed mainly to take place in the metal itself. Such internal heat flow is favored by the configuration of the portions of the head which are thickest at their junction and taper toward the boss 6 and the frame 5 respectively.

The spherically concave inner face of the lid portion 1 makes for minimum metal thickness in the center of the lid portion so as to prevent direct heat transfer from the exhaust to the intake port as far as possible. The lid center, which is at the highest temperature, directly transmits its heat to the side wall for dissipation by the external fins 19, as far as the heat is not carried away by the circulating oil. Heat dissipation by the fins 19 is favored by the upwardly decreasing thickness of the wall portion 4. Proper circulation of the cooling oil is ensured by the upward flaring of the cavity side wall.

It will be understood that the cylinder head with its valve rocker assembly is surmounted by the usual valve gear cover so that the top of the cavity in the cylinder head while open to the entry of oil, need not be open to the atmosphere.

The cylinder head of the invention is of great rigidity because of its shape which is similar to that of an inverted hollow frustum of a cone represented by the wall portion 4, integrally joined to the substantially plate-shaped lid portion 1.

The cylinder head of the invention has been found to resist deformation because of the smaller thermal expansion of the outer fibers of the lid portion 1 which are directly oil cooled. The outward bulging of the cylinder lid in conventional engines operating at high pressures and temperatures is a well known source of incomplete valve closure, and a cracking of the lid face in the combustion chamber. The sharp edges of the recesses for the valve seats and the injection nozzle seat are vulnerable to such cracking in known compression ignition engines. Deformation, crack formation, and the resulting difficulties are safely avoided by our invention.

Obviously, many modifications are contemplated and may be resorted to by those skilled in the art without departing from the spirit and scope of the invention as hereinafter defined by the appended claims, as only a preferred embodiment thereof has been disclosed.

This is a continuation in part of our co-pending application Serial Number 166,663 filed on January 16, 1962, now abandoned.

What we claim is:

1. A cylinder head for an air-cooled internal combustion engine, comprising, in combination:

(a) a head member defining a substantially trough-shaped cavity therein, said head member including a lid portion having two opposite faces, one of said faces constituting the bottom of said cavity, and an annular wall portion extending away from said lid portion and constituting the side wall of said cavity, said cavity having an open top opposite said bottom thereof;

(b) fastening means for attaching said head member to the open top of an engine cylinder in sealing en-

agement of the other face of said lid portion with said cylinder top;

(c) mounting means for mounting a valve rocker assembly on said head member above said open top of said cavity, whereby liquid coolant provided to said rocker assembly flows downward into said cavity; and

(d) a conduit having an orifice in said wall portion communicating with said cavity, said conduit extending downwardly from said orifice for overflow passage of said liquid coolant from said cavity into said conduit, said orifice being adjacent said open top and spaced from said bottom.

2. A cylinder head as set forth in claim 1, wherein said one face of said lid portion is concave.

3. A cylinder head as set forth in claim 2, wherein said concave face is of substantially spherical shape.

4. A cylinder head as set forth in claim 1, wherein said side wall of said cavity flares in a direction away from said bottom and toward the open top of the cavity.

5. A cylinder head as set forth in claim 1, wherein said fastening means include a frame member fixedly fastened to said head member, and through-bolt means for attaching said frame member to said engine cylinder.

6. A cylinder head as set forth in claim 1, further comprising a plurality of ribs integral with said head member and connecting said bottom to said side wall in said cavity, said ribs defining grooves therebetween.

7. A cylinder head as set forth in claim 6, wherein said ribs extend in a direction from said bottom toward said top of said cavity, and said grooves are open toward the top of said cavity.

8. A cylinder head as set forth in claim 1, wherein said wall portion decreases in thickness in a direction away from said lid portion.

9. A cylinder head as set forth in claim 1, further comprising air-cooling fins on said wall portion outside said cavity.

10. A cylinder head for an air cooled internal combustion engine, comprising, in combination:

(a) a head member defining a substantially trough-shaped cavity therein, said head member including a lid portion having two opposite faces, one of said faces being of substantially spherical concave shape and constituting the bottom of said cavity, and an annular wall portion extending away from said lid portion and constituting the side wall of said cavity, said cavity having an open top opposite said bottom thereof and flaring in a direction from said bottom toward said open top, the thickness of said wall portion decreasing in said direction;

(b) a frame member fixedly fastened to said head member;

(c) fastening means for attaching said frame member to the open top of an engine cylinder in sealing engagement of the other face of said lid portion with said cylinder top;

(d) a plurality of ribs integral with said lid portion and said wall portion, said ribs extending from said lid portion in said cavity toward said open top of the cavity and defining therebetween grooves open toward the open cavity top;

(e) air-cooling fins on said wall portion outside said cavity;

(f) mounting means for mounting a valve rocker assembly on said head member above said open top of said cavity, whereby liquid coolant provided to said rocker assembly flows downward into said cavity; and

(g) a conduit having an orifice in said annular wall portion communicating with said cavity, said conduit extending downwardly from said orifice for overflow passage of said liquid coolant from said cavity into said conduit, said orifice being adjacent said open top and spaced from said bottom.

11. A cylinder head as set forth in claim 1 further com-

prising a plurality of ribs integral with said head member and connecting said bottom to said side wall in said cavity, said bottom being arcuately concave in said cavity, and said wall portion decreasing in thickness in a direction away from said lid portion; and air-cooling fin means on
